Primary Examiner — Rosemary K Tarcza*(74) Attorney, Agent, or Firm* — Lathrop GPM LLP;
William T. Griffith**(57) CLAIM**

The ornamental design for a decorative portable power charger with cables, substantially as shown and described.

DESCRIPTION

FIG. 1 is a front perspective view of a decorative portable power charger with cables showing our new design;

FIG. 2 is a front view thereof;

FIG. 3 is a rear view thereof;

FIG. 4 is a left-hand side view thereof;

FIG. 5 is a right-hand side view thereof;

FIG. 6 is a top view thereof; and,

FIG. 7 is a bottom view thereof.

The broken lines shown in the drawings are included for purpose of illustrating portions of the decorative portable power charger with cables that form no part of the claimed design.
